UNITED STATES PATENT OFFICE

HAROLD S. BARNES, OF ALLENTOWN, PENNSYLVANIA, ASSIGNOR TO P. R. BAKER, OF COLUMBIA, PENNSYLVANIA, TRADING AS THE UNITED STATES LOCK AND HARDWARE COMPANY

TOY

Application filed July 23, 1929. Serial No. 380,440.

My invention relates to a novel toy and has more especial relation to the mobile type.

The leading object of the present invention is to provide a brightly decorated toy 5 of the character symbolic of a creeping or crawling insect, crustacean, or similar creature, which toy may be towed along the floor by means of a cord, and wherein the propulsion of the toy causes the rotation of 10 opposite horizontally disposed wheels, simulating feet or claws.

A further object of the present invention is to provide a toy of the character stated in which horizontally disposed rotatable parts 15 symbolic of the feet or claws of a spider, crab, lobster, or the like are employed which rotate during the towing or propulsion of the toy.

A further object of the present invention 20 is to provide a toy of the character stated which may be readily stamped from thin metal to provide an inexpensive article.

A further object is to provide an arrangement, combination, and connection of parts 25 for attaining the results sought by the foregoing objects.

The invention consists of the novel construction hereinafter described and finally claimed.

For the purpose of illustrating my invention I have shown in the accompanying drawings one form thereof which is at present preferred by me since the same has been found in practice to give satisfactory and 35 reliable results, although it is to be understood that the various instrumentalities of which my invention consists can be variously arranged and organized and that my invention is not limited to the precise arrangement and organization of the instrumentalities as herein shown and described.

The nature, characteristic features and scope of the invention will be more fully understood from the following description 45 taken in connection with the accompanying drawings forming part hereof, and in which:

Fig. 1, is a top or plan view of a toy embodying the invention.

Fig. 2 is a view in rear elevation of Fig. 1.

Referring to the drawings in detail, 1 designates the top or body of the toy, which may be oval or elliptical in contour, when viewed from the top, and which in cross-section (see Fig. 2) is arched or convex and horizontally positioned, said member 1 being preferably made of thin sheet metal, or a casting, although papier mâché or the like or other material may be employed, which may be painted a bright color as 55 green to depict the color of a crustacean, insect, crab, or similar creature. The back 1 also has depicted thereon spots 3 symbolic of eyes. Preferably formed integral with the member 1 and projected forwardly 60 therefrom is a pair of oppositely disposed claws or members 4 which may be painted red or any other color contrasting with the color of member 1. In the present instance the members 4 depict the claws of a crab or lobster and the member 1 represents the back of the crab or lobster, so that in this particular instance the member 1 would be painted green and the members 4 painted red. Having pivotal relation with the opposite ends of the member 1 is a pair of 65 toothed wheels 6 upon which the member 1 travels as it is drawn or towed forward by the cord 5, which is attached to the members 4. These toothed wheels are each arranged at an angle with respect to the surface over which the toy is to be drawn and the vertical axes of the wheels are at an inclination to the surface over which the toy is to be drawn, whereby as the toy is drawn forward only the outer arms of the 70 wheels engage the floor surface at the same time, thereby imparting a rotary movement to said wheels.

The wheels 6 each comprises a generally 75 flat or hub portion, and formed integral therewith and radiating therefrom is a plurality of arms 7, which terminate in the flattened or deflected portions 8 for engaging the floor surface. 9 designates the pivot 80 points, which may be any desired form of connection, as a screw, passing through the wheels and top and provided with a nut. These wheels 6 are symbolic of feet of the 85 insect, animal, or similar creature and also 90 95 100

are of a color contrasting with the color of the member 1 and may be readily stamped from one piece of thin metal.

In drawing the toy forward by means of the cord 5 the outer arms only of the wheels frictionally engage the floor surface and are revolved, thus giving the effect of a plurality of moving feet and the entire toy provides a very realistic appearing article, simulating an insect, crustacean or the like.

It will be understood that any desired contrasting colors may be employed for the rotatable member 6 and the back 1, or if desired the same color may be employed for said back and rotating members. It will be understood further that the back or top member 1 can be cast, or, if desired, stamped from sheet metal in a single stamping or pressing operation, and since the rotary members 6 comprising their hubs and radiating arms are substantially identical or alike a single set of dies will suffice to produce the two rotating elements 6 so that my device can be manufactured in large quantities very cheaply, as it only requires an assembling operation to mount the rotatable members 6 in place and secure them and to secure the string 5 in position, all of which can be done by very cheap labor.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention, what I claim as new, and desire to secure by Letters Patent, is:

1. As a new article of manufacture, a toy depicting a crab, crustacean or like creature, the feet of which comprise opposed hubs provided with radial arms constituting wheels the axes of which are inclined with respect to one another and to the surface over which the toy is to be drawn.

2. A toy of the character stated and simulating an animal, comprising a convex top, a pair of hubs pivoted beneath said top at an angle with respect to the surface over which the toy is to be propelled and provided with radial arms constituting wheels, the outer series only of which arms contact with said surface so that said wheels may be rotated around their axes.

3. A toy of the character stated and simulating an animal, comprising a generally elliptical-shaped convex top member, a pair of hubs having radial arms constituting wheels pivoted beneath said member at an angle with respect to the surface over which the toy is to be propelled so that said wheels

may be rotated around their axes, said axes being inclined to each other and to the surface over which the toy is to be propelled, whereby only the outer of said radial arms contact with the surface over which the toy is to be propelled.

4. A toy of the character stated and simulating an animal, comprising a generally elliptical-shaped convex top member, claw-like portions extended forwardly from said member, a towing cord secured to said claw-like members, a pair of oppositely disposed wheels comprising hubs connected to said top member and provided with radial arms, pivoted beneath said member on an axis at an oblique angle with respect to the surface over which the toy is to be propelled so that only the outer series of said arms contact with said surface to rotate said wheels around their axes, said wheels and top being of contrasting colors.

HAROLD S. BARNES.
